UNITED STATES PATENT OFFICE.

JOHN EDWARD THORNTON, OF ROCHESTER, NEW YORK, ASSIGNOR TO JOHN OWDEN O'BRIEN, OF MANCHESTER, ENGLAND.

METHOD OF MAKING CINEMATOGRAPH COLOR-FILMS.

1,245,822.

Specification of Letters Patent.

Patented Nov. 6, 1917.

Application filed June 7, 1913. Serial No. 772,440.

To all whom it may concern:

Be it known that I, JOHN EDWARD THORNTON, a British subject, residing at Rochester, N. Y., United States of America, have 5 invented certain new and useful Improvements in Methods of Making Cinematograph Color-Films, of which the following is a specification.

This invention relates to the production 10 of two-color cinematograph film pictures or positives from a single-width two-color negative of the "alternating" type one color section picture being formed on the front and the other section picture of different 15 color on the back of the film through the agency of some salt of silver, exposure to light effect, and development.

It consists essentially in printing from 20 a single alternating negative on one side and then on the other side of a duplex film sensitized both back and front with a light-obstructing medium, between the sensitized layers and subsequently developing, washing and drying both prints.

25 The invention is an extension of that described in my application filed on the 10th April 1913, Serial No. 760200, in which differently colored section pictures are formed on the back and front of the same piece of 30 film stock, as a duplex film.

There is however an important difference 35 between the two,—in my application filed on the 10th April 1913, Serial No. 760200 two separate negatives are required—one for each color—and they are produced in a double camera, on a double-width strip of negative film, and taken through two color-screens, whereas in this application one negative only is required.

40 Moreover there is no existing business organization at the present time that uses double-width film for producing negatives, though there is no difficulty in doing so, whereas there are already several very large 45 organizations in existence making two-color negatives on the single-strip alternating system.

In producing cinematograph color prints 50 according to this invention any printing process of the "rapid" class can be used, provided images in colors can be obtained either directly or indirectly; but processes of the "slow" class are not suitable on account of the long exposure required.

In the "slow" class would be included 55 those based upon the use of bichromate, iron and similar slow-printing sensitive salts.

In the "rapid" class would be included all processes based upon the direct or indirect use of silver salts. 60

The following are examples of processes suitable for the second or "rapid" class.

(1). Gelatino-silver-bromid (or chlorid) or like emulsions such as now used for regular black and white prints. After the print 65 has been exposed, developed, and washed it may be treated by any one of the following methods:—

A. Its black images may be toned, one side to an orange-red, the other to a blue-green 70 color.

B. The silver may be removed and replaced by dyes, by one of the well-known "substitution" methods; or converted into a salt which re-acts as a mordant on dyes and 75 precipitates them *in situ*.

C. The reduced-silver image may be rendered insoluble by treatment with bichromates; or with a mixture of potassium bichromate, ferricyanid, and bromid; or with 80 potassium bichromate and cupric bromid; then the silver bleached or removed; the unhardened gelatin dissolved and removed by hot water, leaving a hardened gelatin image in varying degrees of relief; and finally 85 the duplex reliefs stained up by suitable dyes—red on one side of the film and green on the other.

Or, D. After hardening and bleaching the silver image as above, the unhardened parts 90 may be dyed up, and then mordanted.

(2). Combined silver-bromid and pigment, as typified by the so-called "carbonograph" process, or a modification thereof which is rather more suitable for picture film 95 images than the ordinary process. The image is printed, developed, and washed as usual; then bichromated and hardened; the silver bleached or else dissolved out; and the unhardened gelatin removed by hot water; 100 leaving a picture in colored pigment. Dye may be used instead of pigment, and the final image mordanted to fix the dye as a permanent "lake."

In the accompanying drawing:—

Figure 1 is a perspective view of a single strip of alternating negative, the odd numbers representing a series of picture sec-

tions for green colors A, and the even numbers representing a series of picture sections for red colors B;

Fig. 2 is a perspective view of a sensitized film adapted to be printed from the negative shown in Fig. 1;

Fig. 3 is a perspective view of a finished film, the pictures B shown thereon being printed from the alternating red colored picture sections B of the negative; and

Fig. 4 is a perspective view of the finished film showing the pictures A' printed from the alternating green picture sections A of the negative.

15 In the following description I will assume gelatino-silver-bromid is used and that the black images are afterward changed to red and green.

The film is coated or sensitized on both 20 front and back faces, thus producing a duplex film, but between the central celluloid base b and one of the sensitized layers a (or it may be both if preferred) a layer c of light-obstructing material, such as water- 25 soluble dye in gelatin, is applied. The purpose of this is to prevent light penetrating to and impressing one film during printing of the other. This color washes out during development, fixing and washing as described 30 in my application filed on the 10th April 1913, Serial No. 760200.

The duplex film is then ready for printing, which in this invention is carried out a little differently from the method in universal use for all standard film, and requiring also a different arrangement of the printing machine feed devices.

The regular type of intermittent printing machine is used, but its feed is so arranged 40 that the printing negative is drawn forward two steps or two pictures for every one step or one picture that the sensitized film is drawn. The result is that section picture No. 1 of the negative is impressed upon the 45 front face of the sensitive film, then Nos. 3, 5, 7, 9, and so on, these impressions A' from the picture sections A of the negative which are, for example, blue green, succeeding each other in close order without blank 50 spaces between.

The two films then before developing, washing and drying pass into a duplicate printing machine, which may be so coupled up to the first that the two are combined to 55 form one co-acting piece of apparatus. In passing from one machine to the other the sensitive film turns over, so that its other sensitive side is presented to the printing negative, which however does not turn. The 60 same procedure in printing is again repeated, but the section picture negatives Nos. 2, 4, 6, 8, and so on are impressed this time, care being taken to see that No. 2 is superimposed upon No. 1 and that the register is accurate, the pictures B' produced in

this operation from the picture sections B of the negative and which are, for example, orange red, being exactly superposed on or registering with the pictures A' produced on the opposite side of the film by the previous 70 printing operation.

Accuracy of register is secured by the perforations in the films and by the feed devices all being exceedingly accurate, and by carrying out the operations with extreme 75 care. This is further facilitated if the films for both the negative and positive records are perforated by the same make of perforator; and still more so if the two-length negative record is drawn forward and perforated two pictures at a time, and the single length positive record one picture at a time. 80

The printed positive film after being printed on both sides is then developed, washed, dried, and finished off with all section pictures on one side red and all on the other side green, or in colors which are substantially complementary. The spaces where no part of the image appears remain transparent and pass white light so that the 90 resulting picture when projected on the screen is composed of white, red, green, and such other shades as are produced by overlapping of the red and green in parts.

To bring the two opposite section pictures 95 in closer contact to one another a thinner celluloid stock may be used, which is afterward strengthened by applying an outer coating of celluloid, gelatin, cellulose acetate, or other varnish to the back and front 100 faces, which also serves as a protection to the printed images by completely inclosing and covering them.

What I claim as my invention and desire to protect by Letters Patent is:— 105

1. The herein described method of producing two-color value positive pictures for cinematograph films, which comprises printing two-color positive pictures of different color values in succession on a single strip 110 of transparent film from a single strip of negative film having the picture negatives of different color values arranged in alternating sequence thereon, the alternating picture negatives of one color value being printed 115 in direct sequence on one side of the positive film and the pictures of the other color value being printed in direct sequence on the opposite side of the positive film, the pictures on opposite sides of the positive film 120 registering, and subsequently coloring the pictures on the positive film in the correct color.

2. The herein described method of producing two-color value positive pictures for 125 cinematograph films from a single strip of negative film having the picture negatives of different color values arranged in alternating sequence thereon, which comprises printing on one side of a transparent film 130

positive pictures from the picture negatives of one color value, and then printing in register on the opposite side of the transparent film the positive pictures from the 5 picture negatives of the other color value, the negative film and positive film being superposed during said printing operations and the negative film being advanced twice the distance of the positive film between the 10 printing of each picture, and subsequently

coloring the pictures on the positive film in the correct color.

In testimony whereof I have hereunto set my hand in presence of two subscribing witnesses.

JOHN EDWARD THORNTON.
